UNITED STATES PATENT OFFICE.

CHRISTIAN A. FISCHER, OF GRAND FORKS, NORTH DAKOTA.

SHOE-HOLDER.

No. 890,131.

Specification of Letters Patent.

Patented June 9, 1908.

Application filed July 19, 1907. Serial No. 384,589.

To all whom it may concern:

Be it known that I, CHRISTIAN A. FISCHER, a citizen of the United States, residing at Grand Forks, in the county of Grand Forks 5 and State of North Dakota, have invented certain new and useful Improvements in Shoe-Holders, of which the following is a specification.

The present invention is in the nature of 10 an improved device for receiving shoes or similar articles of foot wear and holding the same in a convenient position for being blackened or undergoing similar operations.

The invention contemplates a device of 15 this character embodying a pneumatic sack designed to be inflated after being inserted within the shoe so as to distend the shoe and hold it in the position assumed when upon the foot of the wearer.

20 The invention further has for its object to provide a foot-piece carrying a clamp for engaging the sole of the shoe and peculiarly mounted so as to be readily swung into an inoperative position.

25 For a full description of the invention and the merits thereof and also to acquire a knowledge of the details of construction and the means for effecting the result, reference is to be had to the following description and 30 accompanying drawings, in which:

Figure 1 is a perspective view of a shoe holder embodying the invention. Fig. 2 is a longitudinal sectional view through the same. Fig. 3 is a transverse sectional view 35 on the line 3—3 of Fig. 2. Fig. 4 is a similar view on the line 4—4 of Fig. 2. Fig. 5 is a detail view of the locking bolt carried by the split ring.

Corresponding and like parts are referred 40 to in the following description and indicated in all the views of the drawings by the same reference characters.

Specifically describing the invention the numeral 1 designates a base plate which may 45 be rigidly secured to any suitable support and which is provided with the perforated ears 2 and the upper ear 3 formed with a threaded opening. A bracket projects laterally from the base plate 1 and comprises a 50 split ring 4 supported by the lower spaced arms 5 having a hooked engagement with the perforated ears 2 upon the base plate and the upper arm 6 detachably connected to the upper ear 3 by any suitable means such as 55 the thumb screw 7. A sleeve 8 is received within the split ring 4 and is provided toward

its upper end with an annular shoulder 9 designed to engage the upper portion of the split ring and aid the same in properly supporting the sleeve. The lower end of the 60 sleeve 8 may be bent laterally and has a pneumatic sack 10 applied thereto, the said pneumatic sack having the general form of a foot and being designed to be inflated after being inserted within the shoe. The two 65 arms of the split ring 4 are shown as connected to the sleeve 8 by screws 11 and are provided with outstanding ears engaged by a clamping bolt 12 by means of which the said split ring is designed to be contracted and 70 rigidly clamped about the sleeve. The upper end of the sleeve 8 is contracted and threaded as indicated at 13 and receives a perforated cap 14 through which the barrel 75 of an air pump 15 extends, the said barrel being provided with an exterior annular rib 16 designed to be received within a corresponding recess formed at the upper end of the sleeve 8. A washer 17 of rubber or similar material is interposed between the rib 16 and 80 the end of the sleeve 8 and enables an air tight connection to be readily brought about between the pump and the sleeve. The lower end of the air pump 15 carries a tube 18 designed to extend within the pneumatic 85 sack 10 and carrying a valve 19 operating to prevent the air from passing back into the pump.

It will thus be apparent that after the shoe 90 has been placed upon the foot form constituted by the sleeve 8, pneumatic sack 10 and associated members, the said air sack can be inflated through the medium of the air pump 15 and the shoe distended and held in the 95 position assumed when upon the foot of the wearer. After the shoe has been blackened or the desired operation performed thereon air is permitted to escape from the foot form by means of a manually operated valve 20 mounted upon the upper portion of the 100 sleeve 8. This valve 20 is formed with a stem 21 extending through a plug 22 threaded into the valve opening and projects outwardly beyond the plug, the said valve being normally held in a closed position through 105 the medium of a spring 23. A slide 24 is mounted upon the exterior of the sleeve 8 and has the end thereof inclined outwardly so as to engage the stem 21 and force the same inwardly when the slide is moved to 110 the limit of its movement in one direction. When the stem 21 is thus pressed inwardly

the valve 20 is unseated and the air within the pneumatic sack 10 permitted to escape. The said sack then collapses and the shoe or other article of foot wear can be removed 5 from position upon the foot form. In order to prevent the air pump 15 from rotating within the sleeve 8 the exterior rib 16 upon the barrel of the same is provided with a pin or projection 25 designed to engage a corresponding notch in the upper end of the sleeve 8.

A pair of spaced flanges 26 project from the lower portion of the base plate 1 and are provided with the corresponding slots 27, 15 the rear ends of the flanges being connected by a pin or similar stop 28. The rear end of a foot-piece 29 is received between the flanges 26 and carries lateral projections 30 fitting within the slots 27 and designed to engage 20 any selected pair of the depressions 31 in the lower sides of the slots. When the foot-piece 29 is moved outwardly until the projections 30 engage the outer ends of the slots 27 the extremity of the said foot-piece is designed 25 to clear the connecting pin 28 between the flanges 26 and thereby permit the foot-piece to swing downwardly into an inoperative position. It will also be observed that the slots 27 are in communication with passages 32 leading to the outer edges of the flanges 26 and permitting the foot-piece 29 to be entirely detached from a base plate when desired. This foot-piece 29 carries a 30 clamp for engaging the soles of the shoe and in the present instance the clamp is identical 35 in construction with those commonly found upon ice skates, the said clamp being adjustable through the medium of a threaded bolt 33 and being operated by a finger-lever 34. After the shoe has been placed in position 40 upon the foot form and the pneumatic sack 10 inflated the foot-piece 29 is swung upwardly and locked in a raised position by moving it rearwardly until the extremity 45 thereof passes under the pin 28. The clamp carried by the foot-piece may then be caused to engage the sole of the shoe and the latter thereby held rigidly in position for being blackened or any analogous operation. Prior 50 to removing the shoe the pneumatic sack 10 is deflated through the medium of the manually operated valve 20 and the foot-piece 29 swung downwardly into an inoperative position.

Having thus described the invention, what is claimed as new is:

1. The combination of a base, a foot form carried by the base, a swinging foot plate mounted upon the base and adapted to hang 60 in an inoperative position or to be swung into co-operative relation to the foot form.

2. The combination of a base, a foot form carried by the base, a swinging foot plate carried by the base, means for locking the

swinging foot plate in an operative position, 65 and a clamp mounted upon the foot plate.

3. The combination of a base, a foot form carried by the base, a pair of spaced flanges projecting from the base, and a swinging foot piece received between the spaced flanges 70 and adapted to co-operate with the foot form, the said foot piece having an interlocking connection with the flanges whereby it can be locked in an operative position.

4: The combination of a base, a foot form 75 carried by the base, spaced flanges projecting from the base, a member connecting the flanges, a swinging foot piece received between the flanges and having a pivotal and sliding connection therewith, the said foot 80 piece being adapted to co-operate with the foot form and being held in an operative position with respect to the said foot form when moved to throw an end thereof in engagement with the member connecting the 85 flanges.

5. The combination of a base, a foot form carried by the base, spaced flanges projecting from the base and provided with slots, a member connecting the flanges, a swinging 90 foot piece received between the flanges and provided with projections operating within the slots, the said foot piece being adapted to be held in an operative position with respect to the foot form when the projections 95 are moved within the slots to throw an end of the foot piece in engagement with the member connecting the flanges.

6. The combination of a base, a sleeve supported by the base, a pneumatic sack 100 carried by the sleeve, means carried by the sleeve for inflating the pneumatic sack, and a foot-piece mounted upon the base in co-operative relation to the sleeve and pneumatic sack.

7. The combination of a base, a foot form carried by the base, a flange projecting from the base and provided with a stop, and a swinging foot piece having a pivotal and sliding connection with the said flange, the 110 foot piece being adapted to co-operate with the foot form and to be held in an operative position with respect to the said foot form when moved to throw an end thereof into engagement with the before mentioned stop. 115

8. A foot form comprising a sleeve, a pneumatic sack applied to the sleeve, an air pump carried by the sleeve for inflating the pneumatic sack, and a valve for deflating the said sack.

9. A foot form comprising a sleeve, a pneumatic sack applied to one end of the sleeve, a cap applied to the opposite end of the sleeve, and a pump also applied to the opposite end of the sleeve and held in position by the cap, the said pump serving to inflate the pneumatic sack. 125

10. A foot form comprising a sleeve, a

pneumatic sack applied to one end of the sleeve, a pump fitting within the opposite end of the sleeve and carrying an annular rib engaging the extremity of the same, a washer interposed between the annular rib and sleeve, and a cap engaging the sleeve and also engaging the rib to hold the pump in position.

11. A foot form comprising a sleeve, a pneumatic sack applied to the sleeve, means carried by the sleeve for inflating the pneumatic sack; a valve mounted upon the sleeve for deflating the pneumatic sack, and a slide mounted upon the sleeve for operating the valve.

12. A foot form comprising a base plate provided with a pair of spaced ears and also with a third ear, a split ring, a pair of arms projecting from the split ring and having a hooked engagement with the before mentioned pair of ears, a third arm projecting from the split ring and detachably engaging the third ear, and a foot form carried by the split ring.

In testimony whereof I affix my signature 25
in presence of two witnesses.
